UNITED STATES PATENT OFFICE

FRANK E. WAKEFIELD, OF ELGIN, ILLINOIS, ASSIGNOR TO ILLINOIS WATCH CASE COMPANY, OF ELGIN, ILLINOIS, A CORPORATION OF ILLINOIS

VANITY CASE

Application filed December 31, 1928. Serial No. 329,370.

In this invention which relates to a vanity case I have sought to incorporate certain desirable features within a very small compass, and to provide therefor a protective housing which need be no larger than an ordinary watch case. The accomplishment of this end has resulted in a novel arrangement and combination of parts as will hereinafter appear.

A suggestive embodiment of my invention is set forth in the accompanying drawing in the manner following:

Figure 1 is a view in elevation of the vanity case interior as the same appears with the cover opened;

Fig. 2 is a similar view with the sifter plate removed;

Fig. 3 is an enlarged transverse section on line 3—3 of Fig. 1; and

Fig. 4 is a detail in section taken on line 20 4—4 of Fig. 2.

In the present structure I employ a case A which may be circular, or otherwise, and, if desired, very similar in contour and size to a watch case of the present day. Such a case is provided with a bottom 5 and up-standing marginal side walls 6 over which may be arranged a cover B of conventional construction. As shown, the cover which includes a top 7 with depending marginal side walls 8 is hingedly connected at 9 to the case in the usual manner. A catch 10 which is extended from the case is adapted to co-operate with a bar 11 forming part of a bow 12 which is affixed to the cover, and by some such means the cover may be releasably locked in closed position upon the case.

The space within the case and cover is occupied by the several elements which together go to make up the vanity constituents.

Fitted within the case is a platform C which extends across between its marginal walls, this platform being formed of sheet metal which adjacent its periphery is bent up at 15 and then reversed upon itself to extend 45 below the platform at 16 to provide a marginal support therefor. The platform is thus equipped with marginal walls extending both upwardly and downwardly for a particular purpose. Two openings through the plat- 50 form are also provided, one designated as

17, being circular and communicating with the space interiorly of the case below the platform. The other opening 18 which is relatively close to the first opening may be generally circular. As shown, however, 55 across one side of this opening at 19 is extended a portion of the platform in the form of a chord to provide a partial confinement for a compact 20 which is entered through this opening for reception within cup 21. 60 This cup is joined at its edges to the under side of the platform (see Fig. 4) and occupies a portion of the space therebelow within the confines of the case.

Mounted to turn upon the platform is a 65 sifter plate D which is of generally circular form in congruity with the associated parts. A pivot pin 22 provides a central point of connection with the platform, and an up-struck rib 23 may be pressed by the finger to 70 execute the desired turning movements. I provide through the sifter plate a plurality of sifter openings 24 grouped by preference within an area no greater than that of the opening 17 in the platform. When the sifter plate is turned to such position that its sifter openings are in register with the platform opening 17, then loose powder contained within the space below the platform is free to be shaken out. A second opening 25 is also provided through the sifter plate. The location of this opening which is relatively close to the sifter openings 24 is such that it may register with the compact opening in the platform when the sifter plate is turned 85 around to the required position. When so placed, the compact 20 is exposed for use.

Of interest and importance to my invention is the relationship obtaining between the several openings in the platform and sifter plate. 90 Those in the platform are disposed fairly close together, on one side of the pivotal center—roughly about 120° apart, leaving a space of perhaps 240° intervening between the more remote edges. In like manner the 95 two openings in the sifter plate (the sifter openings 24 being considered as a group) are arranged close together, but on an opposite side of the pivotal center when the sifter plate is connected operatively to the platform. The 100

consequence of this arrangement is that the sifter plate may occupy any one of three definite full positions: First, the sifter openings in register with the platform opening 17 and the second opening 25 opposite the imperforate portion of the platform lying between its two openings 17 and 18. In this position powder may be shaken through the sifter openings from the interior of the case. Second, the sifter openings opposite the imperforate platform portion and the opening 25 in register with the compact opening 18 in the platform. In this position leakage of powder is prevented while permitting access to the compact. Third, the sifter openings opposite the compact and the opening 25 in register with the platform opening 17. In this position the compact is guarded while access to the case interior is provided for purposes of powder replenishment or otherwise.

My invention also includes provision for mounting of a full size mirror E in the cover. As shown, this mirror which extends clear across the cover is held in place by a bezel 26. A sufficient space intervenes between the mirror so placed and the sifter plate for the accommodations, if desired, of a puff 27. When so received, the marginal walls upstanding from the platform will assist in maintaining the puff centrally positioned within the case.

I claim:

1. In a vanity, the combination of a case within which is a main compartment surrounded by a platform having two openings distant about 120 degrees, means below one opening defining a second compartment within the other, a sifter plate pivotally mounted to rotate on the platform and provided with two openings distant about 120 degrees, the openings in the platform being on a side of the center which is opposite to that wherein are formed the openings in the sifter plate, the relationship being such that the sifter plate may occupy any one of three rotative full positions in the first of which one sifter plate opening is opposite an imperforate portion of the platform and the other opening is in register with the platform opening leading into the main compartment, in the second of which one sifter opening uncovers the platform opening leading into the second compartment and the other sifter plate opening is opposite an imperforate portion of the platform, and in the third of which one sifter plate opening is in register with each of the platform openings.

2. In a vanity, the combination of a case having a platform defining an enclosed main compartment, means defining also a second compartment within the first, there being openings through the platform into each of the two compartments, and a sifter plate mounted for rotation upon the platform and provided with two openings, the location of

the openings in the platform and sifter plate being such that the latter may occupy any one of three rotative full positions in the first of which one sifter plate opening is opposite an imperforate portion of the platform and the other opening is in register with the platform opening leading into the main compartment, in the second of which one sifter opening uncovers the platform opening leading into the second compartment and the other sifter plate opening is opposite an imperforate portion of the platform, and in the third of which one sifter plate opening is in register with each of the platform openings.

3. In a vanity, the combination of a case over which is extended a platform providing an enclosed main compartment within the case, means defining a second compartment within the first, there being separate openings through the platform into each of the two compartments, and a sifter plate pivotally mounted for rotation on the platform having a set of sifter openings grouped together and a larger opening separated therefrom, the disposition of the openings in the sifter plate in relation to those in the platform being such that the sifter plate may occupy any one of three rotative full positions, in the first of which the sifter openings are opposite the platform opening leading into the main compartment, the other sifter opening being opposite an imperforate portion of the platform, in the second of which the sifter openings are opposite an imperforate portion of the platform and its larger opening is opposite the opening in the platform leading to the second compartment therebelow, and in the third of which the sifter openings are opposite the opening in the platform leading to the second compartment, with the remaining openings in the sifter plate opposite the other platform opening leading into the main compartment.

In testimony whereof, I have hereunto affixed my hand this 27th day of December, 1928.

FRANK E. WAKEFIELD.
